Primary Examiner — Michael C Stout*Assistant Examiner* — Katrina N Gonzalez(74) *Attorney, Agent, or Firm* — Alan D. Kamrath; Karin L. Williams; Mayer & Williams PC(57) **CLAIM**

The ornamental design for a road reflector base, as shown and described.

DESCRIPTION

FIG. 1 is a right front side perspective view of a road reflector base showing my design;

FIG. 2 is a right rear side perspective view of the road reflector base as shown in FIG. 1;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another right front side perspective view, shown in an environment of use.

The broken lines shown in FIGS. 1, 3 and 9 illustrate portions of the road reflector base. The broken lines in FIG. 9, showing the road reflector, illustrates environmental structure. The broken lines form no part of the claimed design.
